[57] CLAIM

The ornamental design for a picture frame or similar article, as shown and described.

DESCRIPTION

FIG. 1 is a front elevational view of a picture frame or similar article showing my new design;

FIG. 2 is a top plan view thereof, the bottom plan view being the mirror image thereof;

FIG. 3 is a rear elevational view thereof, the pattern on the front face not being shown for clarification purposes;

FIG. 4 is a left side plan view thereof, the right side plan view being the mirror image thereof; and,

FIG. 5 is a cross-sectional view taken along line 5—5 of FIG. 1.
